UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

UNDERFRAME FOR CARS.

No. 881,840.

Specification of Letters Patent.

Patented Sept. 25, 1906.

Application filed August 28, 1905. Serial No. 275,379.

To all whom it may concern:

Be it known that I, ETHAN I. DODDS, a citizen of the United States, residing at Pullman, in the county of Cook and State of Illinois, 5 have invented certain new and useful Improvements in Underframes for Cars, of which the following is a specification.

The bolsters and side sills of metallic railway-cars are the subjects of improvement by 10 my present invention, which includes, instead of the usual tension-plate secured to the bolster, one or more tension or tie rods passing through perforations in the center sills and attached to the ends of the bolsters 15 and to the side sills, partially supporting these parts. In conjunction with the center sills a spacer is employed, the tie-rods extending through holes in said spacer, which forms an additional rest or strut over which the 20 rods pass and upon which they're st. Each side sill comprises two longitudinal rolled members, disposed one above the other, and for the under one I preferably employ a Z-beam and for the upper one I use an angle-bar. Such a construction secures the 25 benefits of a single deep sill and acts in conjunction with the side stakes as a plate-girder without any plates.

In the accompanying drawings I have illustrated 30 my invention in a preferred form, like reference characters referring to the same parts throughout.

Figure 1 is a vertical cross-section adjacent to the body-bolster of a car embodying my 35 invention. Fig. 2 is a section of a portion of the car shown in Fig. 1 on the line 2 2, as viewed in the direction indicated by the arrows. Fig. 3 is a plan of a fragment of the underframe of the car and shows in detail the 40 manner of securing the outer end of the body-bolster to the side sill. Fig. 4 is a cross-section of the body-bolster shown in Fig. 1 on the line 4 4, and Fig. 5 is a perspective view of the anchor or tie-plate, one of which is secured 45 to each outer end of the body-bolster and attached to the side sill, the tie rod or rods being fastened to the anchor.

The channel center sills 10 are spaced apart and tied together by member 11, which 50 has a central web 11^a with integral outstanding flanges 11^b on all four edges, the flanges projecting from both sides of the web, as is shown in Fig. 2. An additional channel-

spacer 12 with its flanges projecting upwardly is fastened above spacer 11 to the 55 webs of the center sills, the center sills and the flanges of this latter spacer having perforations in alinement for the passage of the tie-rods, as shown in Fig. 1. The body-bolster beams comprise spaced pressed-steel 60 beams 13 with integral flanges along their upper and lower edges placed with their webs back to back, as illustrated in Fig. 4, each half of the bolster having short tie-plates 14, riveted to the upper flanges of the channel- 65 beams 13. Angle-bars 15 secure the inner ends of the bolster-beams to the center sills, rivets passing through the center sills, the angle-bars, and the flanges 11^b or spacer 11. At their outer ends the bolster-beams have 70 integral flanges 16, which are turned over from the webs of the pressed-steel beams and which are riveted to Z-beam side sills 17 and to the flanges of side stakes 18. A compression-plate 19 is also fastened to the 75 lower flanges of bolster-beams 13, passing under the center sills. At the outer ends of the body-bolster I supply anchors 20, each of which has a vertical portion or flange 21, adapted to fit between and be riveted to the 80 bolster-beams 13, a lower inclined portion or flange 22, intended to lie against and be riveted to the lower flanges of beams 13, a horizontal portion or flange 23 to bear against and be fastened to the lower flange of the Z- 85 beam side sill, and one or more perforated bosses 24.

Instead of the usual tension-plate riveted to the bolster and extending across the center sills I employ one or more tension or tie 90 rods 25, (in the present instance two,) which pass through the perforations of the center sills and channel-spacer 12 with their outer ends fitted in the bosses of the anchor 20, nuts 26 being screwed on their protruding 95 ends to properly hold them in place. It will be observed that these tension or tie rods partially support the outer ends of the bolster-beams and the side sills and are especially effective for this purpose because of 100 their long span or reach.

Above the Z-beam side sills 17 I employ longitudinal angle-bars 27 with their horizontal flanges extending inwardly, these angles also being riveted to the flanges of the 105 side stakes 18. By this construction I se-

cure, in effect, deep side sills, which answer all the purposes of plate-girders, yet employ no plates.

5 Wooden stringers 28 rest upon and are secured to the upper side of the body-bolsters, floor-planks 29 being nailed or otherwise fastened thereto. The upright side and end planks 30 are preferably bolted to the side stakes, as shown in Fig. 1, to form the sides 10 and ends of the car-body.

15 Minor changes in the details of construction will suggest themselves to those skilled in the art, and hence the invention is not limited to the details as shown and described, 15 except to the extent to which they are made the subject-matter of specific claims.

This patent is intended to embrace only so much of the disclosure made herein as is covered by the claims.

20 I claim—

1. In a railway-car, the combination of 25 perforated center sills, a perforated spacer for said sills, a bolster, and one or more tension-rods supporting the outer ends of said

25 bolster and passing through the perforations of said center sills and spacer, substantially as described.

2. In a railway-car, the combination of 30 perforated center sills, a perforated spacer for said sills, a bolster, side sills, and one or more tension-rods passing through the perforations of said center sills and spacer and secured to said side sills, substantially as described.

3. In a railway-car, the combination of 35 perforated center sills, a bolster fastened to said center sills, an anchor secured to each end of said bolster, and one or more tension or tie rods connecting said anchors and passing through the perforations of said center 40 sills, substantially as described.

4. In a railway-car, the combination of 45 perforated center sills, side sills, an anchor secured to each of said side sills, and one or more tension or tie rods connecting said anchors and passing through the perforations of said center sills, substantially as described.

5. In a railway-car, the combination of 50 perforated center sills, a bolster, side sills, anchors secured to said side sills and bolster, and one or more tension-rods passing through the perforations of said center sills and attached to said anchors, substantially as described.

55 6. In a railway-car, the combination of perforated center sills, a perforated spacer for said sills, a bolster, side sills, anchors secured to said side sills and bolster, and one or more tension-rods passing through the perforations of said center sills and spacer and attached to said anchors, substantially as described.

7. In a railway-car, the combination of 60 perforated center sills, flanged bolster-beams,

flanged side sills, anchors secured to the 65 flanges of said side sills and bolster-beams, and one or more tension-rods passing through the perforations of said center sills and attached to said anchors, substantially as described. 70

8. In a railway-car, the combination of 75 perforated center sills, a perforated spacer for said center sills, flanged bolster-beams, flanged side sills, anchors secured to the flanges of said side sills and bolster-beams, 75 and one or more tension-rods passing through the perforations of said center sills and spacer and attached to said anchors, substantially as described.

9. In a railway-car, the combination of 80 perforated center sills, a channel-spacer for said sills, the flanges of said spacer being riveted to said center sills, said flanges also having perforations, a bolster, and one or more tension-rods supporting the outer ends of 85 said bolster and passing through the perforations of said center sills and channel-spacer, substantially as described.

10. In a railway-car, the combination of 90 center sills, a body-bolster comprising spaced beams, an anchor at each end of said bolster with a flange extending between and riveted to said bolster-beams, and a tie-rod secured to said anchors, substantially as described.

11. In a railway-car, the combination of 95 center sills, a body-bolster, side sills with flanges along their lower edges, said bolster being secured to said center sills and side sills, anchors riveted to the flanges of said side sills, and a tie-rod secured to said anchors, 100 substantially as described.

12. In a railway-car, the combination of 105 center sills, a body-bolster comprising spaced beams, side sills with flanges along their lower edges, an anchor at each end of said bolster having a flange extending between and riveted to said bolster-beams and a flange riveted to the flange of one of said side sills, and a tie-rod secured to said anchors, substantially as described. 110

13. In a railway-car, the combination of 115 center sills, a body-bolster comprising spaced beams, flanged side sills, an anchor at each end of said bolster having a flange extending between and riveted to said bolster-beams, a second flange riveted to the flange of one of said side sills, and a third flange riveted to the body-bolster beams, and a tie-rod secured to said anchors, substantially as described. 120

14. In a railway-car, the combination of 125 perforated center sills, a perforated spacer for said sills, a body-bolster comprising spaced beams with flanges along their lower edges, flanged side sills, an anchor at each end of said bolster having a flange extending between and riveted to said bolster-beams, a flange riveted to the flange of one of said side

sills, and a flange riveted to the flanges of the bolster-beams, and one or more tie-rods passing through the perforations of said center sills and spacer and attached to said anchors, substantially as described.

15. A girder side of a railway-car, comprising upright side stakes, and two parallel rolled beams one immediately above the other secured to said stakes, substantially as described.

16. A girder side of a railway-car, comprising upright flanged side stakes, a Z-beam side sill riveted to the flanges of said stakes, and an angle-bar immediately above said Z-

beam and also riveted to the flanges of said side stakes, substantially as described.

17. A side sill for a railway-car, comprising standard, flanged, rolled beams, one immediately above the other, substantially as described.

18. A side sill for a car, comprising a lower Z-beam and an upper angle-bar immediately above and extending longitudinally of said Z-beam, substantially as described.

ETHAN I. DODDS.
